No. 700,969.

Patented May 27, 1902.

C. E. MÜLLER & J. E. JACKSON.

STOP MOTION FOR LOOMS.

(Application filed Dec. 26, 1901.)

(No Model.)

UNITED STATES PATENT OFFICE.

CHARLES E. MÜLLER, OF PATERSON, AND JAMES E. JACKSON, OF NORTH HALEDON, NEW JERSEY.

STOP-MOTION FOR LOOMS.

SPECIFICATION forming part of Letters Patent No. 700,969, dated May 27, 1902.

Application filed December 26, 1901. Serial No. 87,146. (No model.)

To all whom it may concern:

Be it known that we, CHARLES E. MÜLLER, residing in Paterson, and JAMES E. JACKSON, residing in North Haledon, in the county of 5 Passaic and State of New Jersey, citizens of the United States, have invented certain new and useful Improvements in Stop-Motions for Looms; and we do hereby declare the following to be a full, clear, and exact description 10 of the invention, such as will enable others skilled in the art to which it appertains to make and use the same, reference being had to the accompanying drawings, and to letters of reference marked thereon, which form a 15 part of this specification.

This invention relates to looms, and it has reference particularly to ribbon-looms.

The invention has for its object and it consists in an improved form of the controlling 20 mechanism for narrow-ware looms designed to automatically throw off the power of the loom whenever an irregularity occurs in the action of the rack-bar, causing the shuttles or any portion of them to stand between the 25 reeds and the webs at any time while the beating-up is in progress.

The invention is fully illustrated in the accompanying drawings, wherein—

Figure 1 is a top plan view thereof, certain 30 parts being shown in section; and Fig. 2 is a view in side elevation of said invention.

In the accompanying drawings, *a* designates the frame of the loom, *b* the batten carrying the shuttle-blocks *c*, and *d* the breast-beam. 35 One end of the batten is formed with a recess *e*, into which extends and in which moves a projection *f*, which is carried by the rack-bar *g*. This recess is normally closed by a detachable cover *h*, mounted on the batten.

i designates a bracket consisting of a metallic plate which is secured to the projection *f* of the rack-bar *g*, extending therefrom out through a space *j* left between the cover *h* and the batten *b*, and then downwardly parallel 40 with the front face of the batten. Its lower end carries a block or buffer *k*. On the upright *l* of the frame are secured brackets *m* and *n*, from which project lugs *o*. On these lugs rests a block *p*, said block being hinged 45 to the bracket *m* by means of an elongated

link *q*, having pivotal connection both with the block and with the lugs *o* on the bracket *m*.

r designates the shipper-lever of the loom, and *s* is the usual hand-rail which extends across the front of the loom convenient for use 55 in operating the shipper-lever. On this hand-rail is mounted a pin or other projection *t*.

u is an elastic bar secured on the frame at its lower end and projecting upwardly opposite the pin *t*, being flexible laterally. This 60 bar *u* is adapted to be normally held back out of contact with the pin *t* by a hook *v*, which is pivoted on the block *p*, being adapted to be held against a stop *w* by said bar.

In the operation of the loom, if the parts are 65 working regularly, the combined effects of the forward and backward movement of the batten and the lateral reciprocation of the rack will be to cause an arc-shaped movement in the part *k*, with the result that each 70 time the batten moves forward, or, in other words, when the rack is at either of its extremes of movement, the part *k* can advance alongside of the block at either end thereof without engaging it; but if there is an irregularity in the action of the rack the effect 75 will be to bring the two blocks into contact. This will result in the block *p* moving so that the hook *v* will release the elastic bar *u*, whereupon said bar will strike the pin *t* and 80 so move the rail *s*, which will in turn operate the belt-shipper. The power will be thus thrown off, and when it is once thrown off it will be noticed that it will remain so until the hand-rail is thrown over to the left sufficiently to cause the bar *u* to be forced to a 85 position where the hook *v* can be set into re-engagement with it. In order that the block *k* may take squarely and positively against the block *q*, the latter is formed with step-like 90 faces *x*, arranged substantially parallel with the line of movement of the block *k*. Since the line of movement of the block *k* is a curved one, on account of the combined actions of the rack and batten the general contour of the 95 front or stepped portion of the block *p* is also curved. While, therefore, we recognize that it is not new to provide a block whose function is substantially that being referred to with steps, still we believe that the idea of ar- 100

ranging the steps on the block in a curved line, so that the block *k* will be always in its oscillations while normally working spaced from the stepped block a constant distance, 5 is one patentable to us.

Having thus fully described our invention, what we claim as new, and desire to secure by Letters Patent, is—

1. In a stop-motion mechanism for narrow-
ware looms, the combination, with the batten, 10 of a reciprocating part on the batten movable transversely of the movement thereof, an elastic flexible member adapted to actuate the power-controlling mechanism of the loom, a
15 detent normally holding said member retracted, and means, movable with said reciprocating part, for actuating said detent to release said member, substantially as described.

2. In a stop-motion mechanism for narrow-
ware looms, the combination, with the batten, 20 of a reciprocating part on the batten movable transversely of the movement thereof, an elastic flexible member adapted to actuate the power-controlling mechanism of the loom, a
25 hook normally holding said member retracted, and engageable blocks, one of said blocks being movable with said reciprocating part and the other being connected to said hook, substantially as described.

30 3. In a stop-motion mechanism for narrow-
ware looms, the combination, with the batten, of a reciprocating part on the batten movable transversely of the movement thereof, an elastic flexible member adapted to actuate the
35 power-controlling mechanism of the loom, a

hook normally holding said member retracted, and engageable blocks, one of said blocks being movable with said reciprocating part and the other being connected to said hook, the face of one block which is adjacent the other 40 having step-like projections, substantially as described.

4. In a stop-motion mechanism for narrow-
ware looms, the combination, with the batten, 45 of a reciprocating part on the batten movable transversely of the movement thereof, an elastic member adapted to actuate the power-controlling mechanism of the loom, a detent normally holding said member retracted, and means, movable with said reciprocating part, 50 for actuating said detent to release said member, substantially as described.

5. In a stop-motion mechanism for narrow-
ware looms, the combination of two parts 55 adapted to impinge the one against the other to effect the stopping, one of said parts being adapted to move in a curved line and one of said parts, also, having the face thereof adjacent the other part provided with steps arranged in a curved line, substantially as de- 60 scribed.

In testimony that we claim the foregoing we have hereunto set our hands this 24th day of December, 1901.

CHARLES E. MÜLLER.
JAMES E. JACKSON.
